FREDERIC C. BILLINGS, OF HARTFORD, CONNECTICUT, ASSIGNOR TO THE BILLINGS & SPENCER COMPANY, OF HARTFORD, CONNECTICUT, A CORPORATION OF CONNECTICUT

DROP HAMMER

Application filed August 30, 1923. Serial No. 680,129.

This invention relates to drop hammers of the type having a hammer suitably guided for vertical movement, a board connected thereto, lifting rolls adapted to grip the board to raise the same and the hammer, and a friction bar associated with the rolls and adapted to control the gripping engagement thereof on the board. The invention has as its aim to provide, in a machine of this sort, various features of advantage.

One aim of the invention is to provide an improved friction bar and an improved arrangement of parts for connecting the same with the lifting roll or rolls, the bar and the connection therefor being of economical and strong construction, each of the parts being relatively simple in design so that they can be cheaply manufactured. The arrangement is such that the danger of the bar breaking is reduced to a minimum, but, in the event that it should break under the strains and stresses to which it is subjected, it may be readily replaced at a low cost.

Another object of the invention is to provide an improved cushioning or yielding connection between the hammer and the board so that the strains to which the board is subjected are reduced to a minimum.

Other objects of the invention will be in part obvious and in part pointed out hereinafter.

The invention accordingly consists in the features of construction, combination of elements and arrangement of parts which will be exemplified in the construction hereinafter set forth, and the scope of the application of which will be indicated in the appended claims.

In the drawings forming a part of this specification and in which similar reference characters refer to similar parts:

Figure 1 is a front view of a drop hammer in which my improvements are incorporated;

Fig. 2 is a detail view of the roll operating mechanism;

Fig. 3 is a cross section of a hammer and its connection to the board, showing one form of shock absorbing means;

Fig. 4 is a view similar to Fig. 3, but show-

ing a modified form of shock absorbing mechanism.

Fig. 5 is a plan of the essential parts of the head structure, and

Fig. 6 a detail of the friction bar rock link. 55

Referring to the drawings and, more particularly, to Figs. 1 and 2, the machine is shown as having a frame including a pair of uprights 10 and 11 which are formed so as to

provide ways for a hammer 12 to be suitably guided in its rise and fall. Supported by the uprights 10 and 11 is a head 9 in which is mounted the hammer lifting mechanism here shown, for illustrative purposes, as includ-

ing upper and lower pairs or sets 13 and 14 of lifting rolls. The front rolls of each pair are fast on the shafts 25 and 26, respectively. A pair of belt driven pulleys 15 and 16, equally

driven from an adjacent shaft, not shown, are attached to the shafts of the rear rolls, and the front rolls are driven from the spur gears 17^a and 18^a on said shafts meshing with gears

17 and 18 on the front shafts 25 and 26, all of the gears being of equal size so as to drive the rolls at equal speeds. The front rolls are

arranged to be slightly moved, laterally, into and out of engagement with the board 19 which is attached at its lower end to the ham-

mer 12. This lateral movement is accom-

plished (within the length of the intermesh of the spur gears) through the means of ec-

centric bearings 22 and 23 in which the shafts 25 and 26 of the two front rolls 13 and 14, re-

spectively, are journalled. The eccentric bearings are suitably journalled in the head 85

9. The pair of eccentrics 22, in which the opposite ends of the shaft 25 are journalled, are connected by means of a yoke 28. Like-

wise, there is a yoke 29 which connects the eccentrics 23 in which the opposite ends 90

of the shaft 26 are journalled. It will be seen that when the eccentrics 22 and 23 are rotated in a clockwise direction (Fig. 2),

the rolls are withdrawn from the board so

that the hammer is free to drop, and, upon rotation of the eccentrics in the op-

posite direction, the rolls are brought into gripping engagement with the board so as to raise the hammer. It is desirable that the

rolls 13 and 14 be operated substantially in

unison and, therefore, the yokes 28 and 29 are associated together by a connection including one or more links 31 (two being shown in the present instance) and links 35 and 36. Each of the links 31 is pivotally connected at its upper end to the upper eccentric yoke 28 by a pivot member or pin 44 and is provided at its lower end with an elongated hole 32 receiving a pin 33 carried by the yoke 29. The pair of links 35 and 36 are connected together at their adjacent ends by a bearing or bolt 37, and these links are pivotally connected at their extreme ends to the respective eccentric yokes 28 and 29 by the pins 44 and 33, respectively. Connected to the bearing 37 and between the links 35 and 36 is a link bar 38, the lower end of which is guided by a rock link 40 pivoted to the frame as, for instance, at 41. The lower end of the link bar is pivotally connected to the free or outer end of the rock link by a shaft 39. The friction bar 42 is suspended from the shaft 39 and is guided at its lower end in a suitable boss 43 on the upright 11. The rock link 40 has three spaced arms or hubs 40-a, 40-b and 40-c. The lower end of the link bar 38 is positioned between the hubs 40-b and 40-c, and the upper end of the friction bar is positioned between the hubs 40-a and 40-b, the space between these latter hubs being in substantially the same vertical plane as the boss 43 so that the friction bar in front elevation is substantially straight. As shown most clearly in Fig. 1, the links 35 and 36 are bent in opposite directions so that they straddle the upper end of the link bar 38, thus avoiding any eccentric distribution of the forces applied on the yokes 28 and 29.

From the foregoing description, it will be seen that the friction bar is devoid of any lateral twists or turns, which means that this bar may be very easily made and, also, that it is better enabled to withstand the strains and shocks to which it is subjected when the machine is in operation. Heretofore, it has been customary to make the friction bars with difficult bends, that is, the bars were turned in towards the frame and also offset towards the center of the machine, and when such bars had to be replaced this could only be done at considerable expense and usually after costly delay. A friction bar constructed in accordance with the present invention may be very easily replaced at a relatively low cost.

The operation of the drop hammer will be readily understood. Assuming that the hammer is in raised position, when it is desired to cause the hammer to drop, the operator will release certain clamps (not shown) whereupon the hammer will fall. As the hammer approaches the end of its downward stroke, the cam surface 54 on the hammer will push in a plunger 53 and thereby withdraw the latch 51 against the tension of a spring,

not shown, from a shoulder 52 on the friction bar so that the friction bar will fall. When the friction bar falls, it will exert, through the rock link 40 and the link bar 38, a downward pull on the links 35 and 36, causing the eccentrics to rotate in a counter-clockwise direction and thereby bring the rolls 13 and 14 into gripping engagement with the board. The rolls will thereupon lift the board and the hammer. The eccentrics will be moved substantially in unison and, because of the flexibility or loose motion permitted by the slot and pin arrangement 32 and 33, the rolls 13 and 14 can accommodate themselves to the board. When the hammer approaches the end of its upward stroke, it engages the free end of a lever 46 adjustably pivoted to the frame or upright 11 and pivotally connected intermediate its ends to the friction bar 42. When this lever is raised, it moves the friction bar upwardly causing the eccentrics to be rotated in a clockwise direction, which results in the rolls being withdrawn from the board. The friction bar is held in its raised position by the latch 51 until the hammer again drops.

It will be apparent that the rolls are pressed upon the board with equal force by virtue of the relation of the links and that by reason of the rock-link it is possible for the connection with the roll supports 22 and 23 to be made centrally or intermediate of the roll journals, which is the position best suited for imparting equal pressure to both journals of each roll, while at the same time the source of board-gripping pressure can be located at one side of the roll space, upon or in the plane of one of the frame uprights without subjecting any member to undue strain. The intervention of the rock-link between a friction bar and the equalizing linkage 35 and 36 relieves the latter of any possible restraint to its compensating action due to the resistance to lateral displacement of the friction bar; the upper end of the link bar 38 being free to accommodate any position that may be taken by the pivot pin 37. In this respect particularly, the rock-link exercises important functions in any type of board drop hammer, having upper and lower rolls intended to be equally pressed, with a compensating action, against the board, as will now be evident, and it is intended to claim such rock-link broadly as constituting this invention, without limitation to the particular kind of linkage or the particular source of board-gripping pressure. It is one of the features of the rock-link, though not essential thereto, that it possesses a wide pivot base as indicated in Fig. 6, being of considerably greater width than length and is thereby adapted to produce the offset between the link bar and the friction bar, as above explained, to any extent desired without involving excessive strain likely to lead to fracture. The particular design of pressure-

equalizing linkage is not herein claimed, as the same constitutes the subject matter of a copending application Serial No. 660,137, filed August 30, 1923.

5 In accordance with the present invention, an improved shock absorbing or cushioning means is provided between the hammer and the board in order to reduce to a minimum the strains and jars to which the board is subjected when the hammer is dropped onto the lower die. One form which my improved shock absorbing means may take is illustrated in Fig. 3. The board is secured at its lower end in any suitable manner, as by means of a 10 clamp 55, to a rod or post 56 projecting into a cylinder 57 bored in the body of the hammer. On the end of this rod is attached a suitable piston 58 shaped to conform with the lower end of the cylinder 57. The cylinder 57 and 15 the piston 58 form a dash-pot, there being provided suitable grooves 62 in the wall of the cylinder to form passes or ports which permit the air to pass from one side of the piston to the other. About the rod 56 is a coil 20 spring 63 bearing at its lower end against the piston 58 and at its upper end against a block or blocks 64 dovetailed into the upper face of the hammer 12. These blocks also form a 25 guide for the shaft 56.

30 The operation of the shock absorbing mechanism is such that, as the hammer 12 hits the lower die, the motion of the hammer is arrested with such suddenness as to cause the piston to travel downwardly very quickly, thereby 35 blocking off the ports 62 and trapping, in the lower end of the cylinder, a sufficient quantity of air to produce the desired cushioning effect on the board. When the hammer board is gripped by the rolls 13 and 14, the piston 40 will move upwardly relative to the hammer, causing compression of the spring 63, and when this spring has been compressed to the predetermined extent, the piston and hammer will rise in unison. Thus, the board will 45 gradually take up the weight of the hammer instead of being subjected to a sudden shock which would occur if the board were rigidly secured to the hammer. When the piston is thus raised relative to the hammer, communication is established by means of the 50 ports 62 between the space above and below the piston so that there will be sufficient air beneath the piston to absorb the shock when the hammer is again dropped. In order to 55 supply the cylinder with air, there is provided an aperture 65 permitting the cylinder to have direct communication with the atmosphere.

Another embodiment of the shock absorbing mechanism is shown in Fig. 4. In this embodiment, the dash-pot action is practically 60 eliminated, and the shock is mainly absorbed by springs arranged in a novel manner for this purpose. The hammer 12 is provided with a cylinder 57 of the same form as

in the embodiment shown in Fig. 3, and a rod 56' extends through the blocks 64 into the cylinder. The piston, in this case, is in the form of a sleeve 67 which encloses a spring 63' of the general character described 70 in connection with the embodiment shown in Fig. 3 and generally acts for the same purpose. At the top of the piston 67 there is provided a circumferential flange 68 which forms an abutment for a spring 69 coiled about the cylinder 67 and adapted to be compressed between the bottom of the cylinder 57 and the flange of the piston. Thus, when the hammer 12 stops suddenly, as, for instance, when it hits the bottom die, the rod 56' 75 will be forced downwardly into the cylinder, forcing the piston down and compressing the spring 69 which relieves the board 19 of the force of the impact. Upon the application of a sudden force to the rod 56' in an upward direction, the spring 63' absorbs the 80 shock in the same manner as the spring 63 shown in Fig. 3.

Thus, by the above construction, are accomplished, among others, the objects hereinbefore referred to.

As many changes could be made in the above construction and many apparently widely different embodiments of this invention could be made without departing from 95 the scope thereof, it is intended that all matter contained in the above description or shown in the accompanying drawings shall be interpreted as illustrative and not in a 100 limiting sense.

I claim as my invention:

1. In a board drop hammer the combination of a hammer, and hammer board, board-lifting rolls, movable supporting means therefor, a rock link pivoted on the machine frame independently of any roll-supporting means, a friction bar having its lower part guided on the machine frame adjacent the path of the hammer and connected at its upper end to said rock link, a connection between said roll-supporting means and said rock link and means connected with the hammer for automatically moving said bar to produce sustained hammer operation.

2. In a board drop hammer, the combination of a hammer and hammer board, uprights in which the hammer is guided and a roll space above the hammer, board-lifting rolls in said space, movable supporting means therefor, a rock-link pivoted on the 110 machine frame and extended horizontally from a point near the center of the frame to a point near the line of one of said uprights, a friction bar having its lower part guided on that upright adjacent the path of the hammer and connected at its upper end to one side of said rock link, and a connection between said rock link and said roll-supporting means for moving the latter toward the hammer board.

3. In a board drop hammer, the combination of a hammer and hammer board, uprights in which the hammer is guided and a roll space above the hammer, board-lifting rolls in said space, movable supporting means therefor, a rock-link pivoted on the machine frame below said roll space and extended horizontally to a point at one side of said space, a friction bar having its lower part guided adjacent the path of the hammer and connected at its upper end to the side of said rock-link, and a connection between said rock link and said roll-supporting means for moving the latter toward the hammer board.
4. In a drop hammer, a board, a hammer connected thereto, hammer lifting mechanism including a plurality of rolls spaced apart longitudinally of the board, means for moving said rolls into and out of gripping engagement with said board and including eccentrics in which said rolls are journaled, yokes connecting the eccentrics of each roll, a link bar operatively connected to both yokes and extending below the same, means for guiding the lower end of said link bar, and a friction bar having its upper end pivotally connected to the lower end of said link bar.
5. In a drop hammer, a board, a hammer attached thereto, a plurality of sets of rolls spaced apart longitudinally of said board and arranged to move laterally into and out of engagement with said board, eccentric bearings for said rolls, yokes fixed to said bearings, a triangular system of links connecting said yokes whereby said rolls are moved into and out of engagement with said board, a link bar suspended from said system, a pivot member on said link bar, and a friction bar suspended from said member and laterally spaced from said link bar.
6. In a drop hammer, a board, a hammer, a cylinder within said hammer, a rod connected to said board and provided with a sleeve within said cylinder, a spring between said sleeve and said hammer and arranged to be compressed in movement of one direction of said hammer, and a second spring about said rod and within said sleeve arranged to be compressed in opposite movement of said hammer.
7. In a drop hammer, a hammer, a board, a cylinder within said hammer, a rod attached to said board, a sleeve in said cylinder and connected at its lower end to said rod, said sleeve being in the form of a cylindrical shell about said rod, a spring about said sleeve and compressible between said sleeve and said hammer, a second spring within said sleeve, and a block secured to said hammer and arranged to guide said rod and retain said second spring within said cylinder.
8. In a drop hammer, a board, a hammer, a cylinder within said hammer, a rod fastened to said board and extending into said cylin-

der, a sleeve on one end of said rod shaped in the form of a hollow cylinder outwardly flanged at its upper end, a spring between the periphery of said sleeve and said cylinder and adapted to be compressed between said flange and the bottom of said cylinder, and a second spring within said sleeve and about said rod and adapted to be compressed between the bottom of said sleeve and the top of said cylinder.

9. In a board drop hammer the combination with the machine frame and the board, of a reciprocating member for imparting pressure to the lifting rolls, a rock link pivoted on the machine frame for guiding the movement of said member, upper and lower lifting rolls independently movable toward the board, supporting means for said respective rolls, pressure-equalizing means connecting said supporting means to said rock link and pressure-imparting member, and means for automatically actuating said member to produce sustained hammer operation.

10. In a board drop hammer, the combination with the machine frame and the hammer board and upper and lower lifting rollers adapted for equalized pressure upon the board, of supporting means for the journals of said rolls whereby they are moved into lifting positions, operating connections for said means extending downwardly in front of the rolls and including a rock link pivotally mounted on the machine frame below the roll space, and a friction-bar member connected with said rock link in a laterally offset position with respect to said rolls.

11. In a board drop hammer the combination with the hammer board, of a lifting roll, a movable roll support in which the same is journaled at its opposite ends and by means of which it is moved toward and from the board, a link bar connected to said roll support and occupying a position intermediate of the roll journals, a rock link pivoted on the machine frame at one end and connected to and guiding said link bar at its other end, and actuating means for said roll support connected with said rock link at a point laterally spaced thereon from the point of connection of said link bar therewith.

12. In a board drop hammer, having frame uprights, the combination with the hammer board of a lifting roll, a movable roll-support in which the same is journaled and by which it is moved toward and from the board, a vertical link bar connected to said roll support between the lateral limits of the roll space, a rock link connected to said link bar and extended laterally to one side of the roll space, said link being pivoted on the frame of the machine, and a friction bar connected to the laterally extended part of said rock link and extending down alongside of and guided on the adjacent frame upright.

FREDERIC C. BILLINGS.
